UNITED STATES PATENT OFFICE.

JAMES A. BRITTON, OF BETHLEHEM, PENNSYLVANIA.

HOSE PULLER AND WRINGER.

SPECIFICATION forming part of Letters Patent No. 760,952, dated May 24, 1904.

Application filed June 9, 1903. Serial No. 160,675. (No model.)

To all whom it may concern:

Be it known that I, JAMES A. BRITTON, of Bethlehem, in the county of Northampton and State of Pennsylvania, have invented certain new and useful Improvements in Hose Pullers and Wringers; and I do hereby declare the following to be a full, clear, and exact description of the invention, such as will enable others skilled in the art to which it appertains to make and use the same.

This invention relates to certain new and useful improvements in hose pullers and wringers, and is designed more particularly for use in connection with fire-hose.

The common method of cleaning fire-hose is either to pass it through one of the mechanical washers designed for that purpose or else to unreel the hose after returning to the quarters from a fire and turn a stream of water thereon. Both of these methods are open to serious objections, the first because the hose must be reeled upon the carriage or laid in the hose-wagon, as the case may be, before an opportunity is given to even partially dry the same. Hence it is necessary to again unreel the hose in order that the same may be hung in the drying-tower to be dried out. The second method and, in fact, both methods are open to the objection that it is necessary for the firemen to handle the hose while it is wet and dirty, thereby soiling their uniforms and often times damaging the same irreparably.

It is the object of the present invention to overcome these objections by providing a device which will serve to wring out the excess moisture and by which the hose may be drawn to the hose-carriage and reeled or folded without the necessity of the firemen touching the same while in a soiled condition.

To this end the invention will be herein-after fully set forth, and particularly pointed out in the claims.

In the accompanying drawings, Figure 1 is a side elevation of my improved hose puller and wringer. Fig. 2 is a front view thereof. Fig. 3 is a rear view thereof.

Referring to the drawings, 10 is a standard comprising a base 11 and side pieces 12, united by a top piece 13. Mounted in the lower portion of said standard is a shaft 14, upon which

are mounted two spaced-apart disks 15, connected by rods 16, preferably covered with rubber or other soft material. These disks and their connecting-rods form the driving-drum D, the ends of shaft 14 being squared to receive crank-handles 17.

Mounted in guideways 18, formed in the side pieces 12, is a frame 19, in which is mounted the pressure-drum 20. Said drum comprises a shaft 21, on which are mounted two spaced-apart disks 22, connected by rods 23, the same being curved inwardly at 24 and covered with rubber or other suitable material. The shafts 14 and 21 are geared together in any suitable manner, the form of gearing shown being sprockets 25, keyed to the respective shafts and operated by a chain 26, passing around an idle sprocket 27.

The frame 19 is provided with a guide-rod 28, extending through an opening 29 in the top piece 13, said rod being surrounded by a coil-spring 30, the pressure of which is regulated by a plate 31. Said plate is held normally against movement by arms 32, rigidly mounted on a rock-shaft 33, supported by arms 34, secured to the side pieces, the arms 32 being pivotally connected to depending members carried by said plate. To the outer end of the rock-shaft 33 is rigidly secured a curved arm 35, having a concave portion 36 and an outwardly-curved end 37, the latter bearing against a roll 38, loosely mounted on shaft 21. If desired, antifriction-rolls 39 may be employed to reduce the friction on frame 19. A handle 40 is provided for convenience.

In practice my improved hose puller and wringer is designed to be carried by the hose carriage or wagon, as the case may be. After a hose has been used at a fire the same may be washed by means of a mechanical hose-washer, such as described in Letters Patent No. 689,059, granted to me December 17, 1901, and as the hose leaves the washer the same is passed between the drums D and 20, the spring 30 serving to maintain sufficient pressure between said drums to cause the hose to be fed forward when the drums are rotated. As the couplings on the hose pass between the drums the spring 30 yields sufficiently to allow said couplings to pass free between said drums,

the inwardly-curved portions 34 taking over the form of the coupling. The pressure on the upper drum is uniformly maintained by the curved arm 35, the pressure being increased or diminished according to the position of the frame 19 and the point of engagement of said arm against the roll 38. Thus it will be seen that a uniform pressure is maintained against the hose at all times irrespective of the thickness of the fabric, whereby all excess moisture is forced out as the hose passes between the drums.

The advantages of my invention are at once apparent to those skilled in the art to which it appertains. It will be particularly noted that my invention is simple in construction and of such compact form that the same may be readily carried by a hose-carriage or hose-wagon, that all excess moisture is thoroughly driven out of a hose as it passes between the drums, that provision is made for the ready passage of obstructions, and that the pressure on the drums is uniform irrespective of the thickness of the hose. It will also be noted that while I have described my invention as particularly adapted for use in connection with the washing of fire-hose, yet I do not limit myself to such use nor to its use in connection with fire apparatus, as the same may be employed for hose of any kind, the said invention being primarily designed to avoid the necessity of touching hose of any character while in a soiled condition.

I claim as my invention—

- 35 1. A device of the character described, comprising a frame, drums mounted therein, means for maintaining a pressure between said drums, and a governing device for said pressure means operated by one of said drums.
- 40 2. A device of the character described comprising a frame, a stationary drum, a second drum mounted to reciprocate in said frame, means for maintaining a pressure between said drums, and a governing device for said pressure means operated by said reciprocating drum.
- 45 3. A device of the character described comprising a frame, a drum mounted therein, a second frame mounted to reciprocate in said former frame, a drum carried thereby, means for maintaining a pressure upon said reciprocating frame, and a governing device for said pressure means operated by said second drum.
- 50 4. A device of the character described, comprising a main frame, a drum mounted therein,

a second frame mounted to reciprocate in said main frame and carrying a drum, a guide-rod extending from said reciprocating frame, a coil-spring encircling said rod, and a governing device for said spring operated by said second drum.

5. A device of the character described, comprising a main frame, a drum mounted therein, a reciprocating frame also carrying a drum, a guide-rod extending from said reciprocating frame, a coil-spring encircling the same, a plate loosely mounted on said rod, and means operated by said second drum for regulating the tension on said spring.

6. A device of the character described, comprising a frame having a drum mounted therein, a second frame reciprocating in said former frame and carrying a drum, a rock-shaft, connections between said rock-shaft and said reciprocating frame whereby a pressure is maintained against the latter, and means for automatically regulating said pressure, as set forth.

7. A device of the character described comprising a main frame, a reciprocating frame, drums mounted in said frames, a spring pressing against said reciprocating frame, a plate acting on said spring, a rock-shaft, connections between said plate and said rock-shaft, and a member connected to said rock-shaft and spring to automatically govern the position of said plate, as set forth.

8. A device of the character described, comprising a frame, a reciprocating frame mounted therein, drums carried by said frames, a roll carried by said reciprocating frame, a rock-shaft, connections between said rock-shaft and said reciprocating frame whereby a pressure is maintained against the latter, and a curved arm connected to said rock-shaft and bearing against said roll, whereby said pressure is automatically regulated, as set forth.

9. A device of the character described, comprising a frame, a stationary drum mounted therein, a second drum mounted to reciprocate in said frame, said latter drum having inwardly-curved or concave portions, and means for rotating said drums in unison, as set forth.

In testimony whereof I have signed this specification in the presence of two subscribing witnesses.

JAMES A. BRITTON.
